5 Claims. (Cl. 46—202)

My invention relates to amusement devices for young children and has particular reference to a toy wherein vehicles are driven by an endless string along any pre-selected path. The device is intended to be operated by children aged 3 to 7.

I have observed that young children of the three to seven year old group are fascinated by moving vehicles. Electric trains, wind-up automobiles, electric motor boats, etc., have an unusual attraction and tend to keep them more occupied than other toys do. Usually, however, children of this age lack the manual dexterity to operate these devices and as a consequence either injure the toys or are forced to watch some older person operate the toy for them. For example, when an electric train falls off of the track or is short circuited, etc., it is usually beyond the ability of the normal three to seven year old to place it accurately upon the tracks. As a result, the circuit is shorted or the train otherwise refuses to run. Also, the child soon loses interest when others operate the train or the child is unable to operate it himself.

For this reason I have sought to devise a vehicle toy that is simple enough in construction and operation to permit young children to operate it. I have discovered that an endless string toy of variable size of layout satisfies these requirements and yet is highly attractive to the children. No fixed track or vehicle pattern is required, thus giving great flexibility of layout. The separate parts may be collected into a small package and conveniently and easily stored when not in use. The child maintains interest because the path of travel is not limited in length or direction. The toy can be operated in one room or through a series of rooms. It can be assembled in a few minutes and taken down just as quickly.

Generally speaking, my invention includes a plurality of wheels or drums mounted for rotation in a horizontal plane on independent vertical axes. One of the wheels may be powered as by an electric motor, and all of the wheels are interconnected by a string or its equivalent. The one powered drum drives the others by means of a string which acts as an endless drive belt. Vehicles are attached to the string in any convenient manner and are towed along the path of the string. As the vehicles encounter the drums they merely follow the periphery of the drum until they reach the taut string path leading to the next drum. In this fashion the vehicles travel the path of the string, over and over again depending upon the wishes of the operator.

It is a general object of my invention to provide a path system for powered vehicles that is simple and flexible.

Another object is to provide a path for powered vehicles that can be varied by simply moving rotatable drums or wheels.

Another object is to provide a moving vehicle toy wherein vehicles are moved by an endless belt or string and the vehicles and string mechanism are supported by any floor surface desired to be used.

A further object is to provide a simple and reliable

connector between vehicles and string that permits easy riding of the vehicle about drums that define a string path.

Other objects and advantages of my invention will be apparent in the following description and claims considered together with the accompanying drawings in which:

Fig. 1 is a plan view of an illustrative form of the apparatus including four rotatable drums interconnected by an endless belt or string;

10 Fig. 2 is an enlarged plan view of the driving drum of Fig. 1;

Fig. 3 is an elevation view of the driving drum of Fig. 2 viewed from the direction of the arrow III of Fig. 2;

15 Fig. 4 is an enlarged elevation view of one of the idler drums of Fig. 1;

Fig. 5 is an elevation view in full section through a presently preferred type of vehicle adapted to be towed by the endless belt; and

20 Fig. 6 is a transverse sectional view along the line VI—VI of Fig. 5.

Referring to Fig. 1 it is one of the features of the invention that no mechanical structure is required to interconnect the various rotatable elements and accordingly the entire mechanism may be disposed on a flat horizontal surface such as a table top or a flat floor in a dwelling, or upon carpeting disposed on the floor. This flat surface is indicated schematically by the reference numeral 10 in Fig. 1. Disposed on the floor

25 10 may be a driving drum 11 and one or more idler drums 12, 13, and 14 disposed at random upon the floor 10 according to the desires of the operator. Each idler drum may have a tab 16 connected thereto by a string 17 or other connector and, as required, the leg of

30 35 a chair or other piece of furniture may be placed on this tab 16 to help maintain the idler drum in position. A piece of string 18 is then passed about all of the drums 11, 12, 13, and 14 and tied to an appropriate length and the drums are moved sufficiently to tighten the string

35 40 so that the string will frictionally engage the drums. Vehicles 19 are then connected to the string in any suitable manner so that the string 18 will tow the vehicles about the path of this endless string 18.

Illustrated in Figs. 2 and 3 is an enlarged view of a presently preferred form of the driving drum 11. The drum may have an elongated base 21 upon which is mounted an off-on switch 20 disposed in a conductor 15 leading to an electric motor 22. The electric motor 22 has a rotatable drive shaft 23 which, in turn, drives a friction wheel 26 by friction. This friction wheel 26

50 55 may frictionally engage an interior surface 27 of a rotatable drum 31. The drum 31 may have a grooved periphery 32 which is engaged by the string 18 and the entire drum 31 may be supported on a central hub 33 resting on a tapered bushing 28 rotating on pin 34 secured to the motor 22. A lock ring 35 on the upper end of pin 34 may secure the assembly together.

It will be apparent that the motor drive described is of the type conventionally found on phonographs and the driving mechanism may slip if the rotation of the drum is arrested, thus preventing the motor from burning out or otherwise becoming damaged.

I have found that young children are additionally attracted by having a number of objects disposed upon one or more of the rotatable drums and a great deal of attraction occurs when these objects are figures 38 of men or other persons that may be bodily picked up by the children and inserted in the driver's seats of the vehicle 19 being drawn along the path of the string 18. Other types of objects 39 may also be employed if desired. Pins 41 may be disposed on top of the driving drum 31 to hold these different objects 38 and 39.

Illustrated in Fig. 4 is an enlarged view of a presently preferred form of idler wheel for the idler wheels 12 and 13 and 14. This may include a base member 42 which is centrally apertured at 43 to receive a pin 44. A rotatable drum 46 may have a generally vertical axis of rotation which is accomplished by means of a hub 47 supporting the pin 44. The outer periphery of the drum 46 is preferably grooved in a shallow groove as in 48 to receive the string 18. The pin 44 may be held by the rotatable drum 46 and may be retained in the base 42 by means of a snap ring 49 or other suitable releasable fastener.

Illustrated in Figs. 5 and 6 is a presently preferred form of vehicle for attachment to the string 18. This form of vehicle employs removable axle and wheel assemblies so that the string can be snapped into the vehicle without breaking the string. Accordingly, a vehicle body 51 may have downwardly extending axle supports 52 which are notched at 53 to receive an axle 54. The child or other person operating the entire toy merely pulls on the axle 54 causing it to elastically unsnap from the axle supports 52. The vehicle body 51 is then placed over the string 18 and the axles 54 snapped back into place as shown in Fig. 5. The string 18 then passes through the vehicle and frictionally engages the vehicle because of downwardly extending body portions 51a that deflect the relatively taut string from a straight path. Suitable wheels 56 may be connected to the axles 54.

As illustrated best in Fig. 1 it will be apparent that this mode of connecting the vehicles to the string 18 permits the vehicles to ride about the various idler drums or wheels 12, 13, and 14. As the vehicles pass around the drum 12 the string will be pressed toward one side of the vehicle and the entire vehicle will be pressed against the side of the drum 12 to be carried about the drum on its periphery. As the vehicles pass to the drum 13 the string will pass to the opposite side of the vehicle permitting the vehicle to be held closely against the periphery of that drum but on the opposite side thereof.

My drums may be constructed of any suitable material. These may be formed of pressed cardboard, metal, or other relatively rigid materials. I prefer, however, to make them of a pliable plastic so that they will not break when they are stepped upon or otherwise deformed from their normal shape. The peripheral grooves 32 and 48 of the drums may be roughened to enhance the frictional engagement with the string 18, or they may be coated with latex or other rubberlike material giving a firm frictional engagement with the string 18. Suitable vent holes 29 may be provided in the drum 31 to permit circulation of air to cool the motor 22. The base 21 of the driving drum 11 is preferably beveled as illustrated to permit the vehicles to ride over this base.

It will be apparent to those skilled in the art that any suitable drive mechanism may be employed for the driving drum 11 and conventional phonograph drives are relatively inexpensive and are available on the market. The vehicles 19 are preferably specially constructed so that their fenders fit the drum grooves as illustrated in Fig. 6. Alternatively, toy autos available on the market can be used. The vehicles 19 may be autos, trains, satellites, or wheel boats. Any suitable means of connecting the vehicles to the string may be employed such as clips, etc. Nor need the vehicles be wheeled vehicles but could be simulated animals, airplanes, covered wagons, etc. Any number of vehicles may be attached to the string 18 as desired and they may be spaced along

the string 18 by merely sliding the vehicle along the string whether it is moving or stationary. The string may be stopped at any time by stepping on it. Different motifs may be created as between the drive drums and the vehicles. For example, Indian villages may be set up on the drums 11, 12, 13, and 14 and Indians riding horseback may be the vehicles 19 attached to the string.

For these and other reasons I do not wish to limit myself to the precise embodiment shown but claim all modifications and variations thereof as fall within the true spirit and scope of my invention.

I claim:

1. A powered vehicle toy adapted to be assembled on a floor, or other horizontal surface, comprising: a base, 15 a driving drum mounted on said base for rotation about a vertical axis, motor means on said base drivingly connected to said drum to rotate said drum on its axis, a plurality of idler drums each mounted on a base to rotate on a vertical axis, an endless belt frictionally engaging 20 the peripheries of said drums, said bases each being of such configuration that it is adapted to be located at any point on said horizontal surface so that said drums are independent of each other for selective location on said horizontal surface whereby said belt may be caused to 25 describe a sinuous path, and at least one vehicle, means incorporated in said vehicle to frictionally engage said belt against substantial longitudinal movement along said belt but without substantial resistance to lateral movement of said belt with respect to said vehicle, whereby 30 said vehicle may readily follow the sinuous path of said string about said drums.

2. The toy of claim 1, including a length of string for each said drum and in which one of said strings is secured to the base of each said drum, and a plurality of 35 tabs, one said tab being secured to the other end of each of said strings whereby said bases may be restrained from motion when the toy is in operation by placing a substantial weight on each of said tabs.

3. The toy of claim 1 in which said vehicle has a pair 40 of axle supports adjacent the front end of said vehicle and a pair of axle supports adjacent the rear end of the vehicle, an axle carrying a pair of wheels removably mounted in each said pair of axle supports, said vehicle also provided with a downwardly extending horizontal 45 portion extending downwardly beyond the horizontal plane of said axles when in position on said axle supports whereby said vehicle may be removably frictionally mounted on said belt.

4. A toy as specified in claim 1, wherein the endless 50 belt is a string.

5. The combination as set forth in claim 2 wherein said vehicle is provided with at least one removable axle so that the vehicle may be connected to the endless belt by 55 removing the axle and disposing the belt between the axle and the vehicle.
